UNITED STATES PATENT OFFICE.

ABBOT A. LOW, OF HORSESHOE, AND HARRY HERTZBERG, OF NEW YORK, N. Y.,
ASSIGNORS TO ABBOT A. LOW, MAURICE J. WOHL, AND HARRY HERTZBERG, TRUS-
TEES.

DESIGN FOR A HEATER OR SIMILAR ARTICLE.

42,692.

Specification for Design.

Patented July 2, 1912.

Application filed March 30, 1912. Serial No. 687,506. Term of patent 7 years.

To all whom it may concern:

Be it known that we, ABBOT A. Low, a citizen of the United States, and resident of Horseshoe, St. Lawrence county, and State of New York, and HARRY HERTZBERG, a citizen of the United States, and resident of the city of New York, borough of Brooklyn, county of Kings, and State of New York, have invented a new, original, and ornamental Design for Heaters or Similar Articles, of which the following is a specification, reference being had to the accompanying drawing, forming part thereof.

The figure is an elevation in perspective of a heater, showing our new design therefor.

The design comprises a circular base hav-

ing a centrally located vertical member at the top of which is mounted a circular inverted dish shaped member. Around the periphery of the base a number of vertical rods rise above the dish shaped member and bend inwardly at the top, joining a disk shaped member at the center, forming a guard, substantially as shown in the drawings.

We claim:

The ornamental design for a heater or similar article, as shown and described.

ABBOT A. LOW.
HARRY HERTZBERG.
